UNITED STATES PATENT OFFICE

2,453,955

REMEMBRANCER

James Leslie Younghusband, Chicago, Ill.

Application June 5, 1947, Serial No. 752,786

2 Claims. (Cl. 63—15)

1

My invention relates to a ring having means for reminding the wearer of a resolution.

It often happens that a person who enjoys a drink of intoxicating liquor tends to forget the number of drinks he takes in the excitement of kindred company or a celebration, and before he realizes it he has become intoxicated. If the same person had some pleasant, attractive, yet silent and unobtrusive remainder of the number of drinks he was taking at the time, he would know when to stop and would voluntarily do so. Such a remembrancer is the object of this invention.

While my reminding means is designed primarily to solve the foregoing problem yet it may be used for other purposes and to solve other problems and has such other objects, advantages and capabilities as will later more fully appear and which are inherently possessed by my invention.

While I have shown in the accompanying drawings a preferred embodiment of my invention, yet I wish it understood that the same is susceptible of modification and change without departing from the spirit of my invention.

Referring to the drawings, Fig. 1 is a side view of a ring embodying my invention with the jewels covered; Fig. 2 is a detailed sectional view of the same; Fig. 3 is a side view of the ring with the jewels exposed; Fig. 4 is a top plan view of the ring with the jewels exposed; Fig. 5 is a detailed sectional view on line 5—5 of Fig. 2 and Fig. 6 is a detailed sectional view on line 6—6 of Fig. 2.

The preferred embodiment selected to illustrate my invention comprises a ring 10 having set therein five spaced stones. The first three of these stones 11, 12 and 13 are white in color and preferably diamonds. The fourth stone 14 is green in color and preferably an emerald. The fifth stone 15 is red in color and preferably a ruby.

A cover 16 of sufficient size to cover said stones is slidably mounted on said ring 10, and is adapted to be moved to expose one or more of said stones. Spaced holes 17 are provided to aid in moving the cover 16.

My cover may be stopped at any point after it has been manually moved by the user and will remain in position due to friction grip with the ring, or any other suitable stop expedient.

In use let us say that the wearer is attending a celebration at which liquor is to be served. Upon taking a drink the wearer moves the cover to expose white stone 11. After another drink he exposes white stone 12 and after a third drink white stone 13. When he takes his fourth drink and moves the cover to uncover green stone 14, the color warns him that he is nearing the end of his drinking. Then when the wearer takes his fifth drink and turns to the danger signal exhibited by red stone 15, he knows that he has

had enough drinking for the night. While he is still sober he has been quietly warned without embarrassment and takes no further drinks.

My device may vary with the body member in other forms than that of a ring. Other indicia may be used in place of the stones. Such indicia need not be limited to five in number, so that any appropriate number may be used.

Having thus described my invention, I claim:

1. A remembrancer comprising a ring, five spaced stones mounted in said ring, a cover slidably mounted on said ring, said cover adapted to normally cover said stones, the stone on one end being white and followed by two white stones, one green stone and one red stone, the stone on the opposite end being red, said cover adapted to be manually moved by the user in one direction to expose first the end white stone, then successively in order two white stones, three white stones, three white stones and the green stone and finally three white stones, the green stone and the red stone, said cover adapted to be moved by the user in the opposite direction to cover all of the said five stones.

2. A remembrancer comprising a ring, five spaced stones mounted in said ring, a cover slidably mounted on said ring, said cover adapted to normally cover said stones, the stone on one end being white and followed by two white stones, one green stone and one red stone, the stone on the opposite end being red, said cover adapted to be manually moved by the user in one direction to expose first the end white stone, then successively in order two white stones, three white stones, three white stones and the green stone and finally three white stones, the green stone and the red stone, said cover adapted to be moved by the user in the opposite direction to cover all of the said five stones, said cover having flanged portions engaging opposite sides of the ring, said cover having a plurality of spaced openings to aid the user in moving said cover.

JAMES LESLIE YOUNGHUSBAND.
